UNITED STATES PATENT OFFICE.

HONORÉ HAMPE, OF NEUILLY-SUR-SEINE, FRANCE.

BACKING-OFF LATHE.

1,320,468.

Specification of Letters Patent.

Patented Nov. 4, 1919.

Application filed June 5, 1918. Serial No. 238,338.

To all whom it may concern:

Be it known that I, HONORÉ HAMPE, a citizen of the Republic of France, residing at 6 Rue de l'Urbaine, Neuilly-sur-Seine, France, have invented certain new and useful Improvements in Backing-Off Lathes, of which the following is a specification.

The present invention relates to backing off lathes and is an improvement on existing lathes of a similar type.

The drive of various members is obtained by means of a main driving shaft carrying three toothed pinions which each drive a group of different members. This method of grouping effects an easier and quieter operation of the lathe. The controlling shaft of all the members rotates the quickest and all the drives are effected through speed reducing gearing so that there is thus obtained in the present lathe, movements which permit of the execution of precision work without jerks or shocks.

The distribution of the driving force is directed from the main controlling shaft to the three essential members of the machine.

The first pinion on the general controlling shaft drives through a gearing which transmits the desired reduction in speed to the spindle of the fixed headstock.

The second pinion on the main controlling shaft drives the lead screw for the longitudinal movement of the saddle through a reversing arrangement and gearing.

The third pinion on the main controlling shaft drives the cam for the movement of the saddle through differential gear, helicoidal gearing, a worm and gearing.

The differential gear serves to give to the backing off saddle a movement in advance or a delayed movement so as to follow the helix of the cutters with the lead screw.

The arrangement of this member between the main driving shaft of the machine and the backing off cam characterizes the present invention.

The general controlling shaft carries a stepped pulley which receives its movement from a suitable source of power.

The backing off saddle drive is obtained by a cam arrangement, a tappet, a lever and a wedge adjustable from the exterior of the machine which permits an adjustment of the backing off depth by the movement of a screw which displaces the wedge on the face of the lever controlling the backing off saddle.

The exterior of the saddle carries a scale which indicates the depth to which the cutting is adjusted.

Figure 1 of the accompanying drawing is 60 a longitudinal vertical section of the machine.

Fig. 2 is a vertical section on the line *a—b*.

Fig. 3 is a horizontal section on the line 65 *c—d*.

Fig. 4 drawn to an enlarged scale is a cross section of the saddle on the line *e—f*.

Fig. 5 is an end view of the saddle drawn to the same scale as that of Fig. 4.

The frame A of the lathe Figs. 1, 2, 3, 4, 70 5 is fitted as a single piece with the body of the fixed head-stock as in an ordinary lathe.

The spindle B, Fig. 1 of the fixed head-stock is constructed as in a lathe.

The same applies to the tail-stock C, 75 Fig. 1.

The spindle B Fig. 1 carries a large toothed driving wheel D, Figs. 1 and 2, which receives its movement from a pinion E, Fig. 2.

The pinion E is secured to its shaft which carries at its end a removable toothed wheel F.

The wheel F receives its movement from a pinion C, Figs. 1, 2, through the toothed wheels H and I integral with or secured to each other. The wheels H and I are arranged on a radial or change gear plate J fixed to the back of the lathe A. The wheels F, H and I can be replaced by other wheels 85 having a greater or less number of teeth so that the speed of rotation of the spindle B can be varied relatively to the main driving shaft K, Figs. 1, 2 and 3. According to the number of teeth of the cutter that it is desired to back off the relation above indicated is varied as desired.

The main driving shaft K carries a stepped pulley L Figs. 1 and 3 which is rotated in any suitable manner.

On the main driving shaft K are fixed two other pinions M, N, Fig. 3 one of which M controls the lead screw V through the reversing gear O, Fig. 1, its shaft P, Fig. 1, gear Q, and the gear R, Figs. 2 and 3, and the other pinion N drives the cam S of the reproducing carriage through the wheel T, Figs. 1 and 2 the bevel wheel U integral therewith planetary pinions W of the differential gear and the shaft Y.

The wheel T rigid with the bevel wheel U and the worm wheel T' turns on the shaft

- Z which is supported in the frame A of the lathe. The worm wheel T' communicates its movement to the helicoidal pinion R' with which it gears. The pinion R' is keyed 5 on the shaft Q' which communicates its rotational movement to the shaft O' Fig. 1 through the gear P' Figs. 1 and 3. The shaft O' is provided with a worm V' which drives the wheel N' rigid with the bevel 10 pinion U which communicates this movement to the bevel planetary pinions W of the differential. According to the nature of the gear P', the bevel pinion U receives a movement in proportion to that of the bevel 15 pinion U. The proportion of the teeth on the gear P' is calculated according to the pitch of the helix of the cutter to be formed.
- For backing off straight cutters the movement of the bevel pinion V' is blocked and 20 the gear P' is disengaged from its wheels. The shaft Q' and the helicoidal wheel R' turn freely during this operation.
- The cam S of the reproducing saddle is arranged on the feathered shaft Y on which 25 it can slide in accordance with the longitudinal movement of the saddle.
- The cam S actuates the lever A' Fig. 4 through a tappet B'.
- The lever A' is articulated on the base C' 30 of the reproducing saddle D'. The base C' of the saddle can turn about the axis y—y in order to give various inclinations in a horizontal plane to the saddle D' and the base C'.
- On the reproducing saddle D' Fig. 4 is 35 fixed a grooved support E' in which there slides a guide block F'.
- By means of the screw v which is held in 40 the direction of its length by the cover piece p, the slide block F' can be adjusted in the support E' along the face of the lever A'. When the slide block F' is lowered it approaches the point of contact with the lever 45 at the center and consequently diminishes the stroke of the saddle D' and inversely when the slide block is raised. The slide-block F' support N' and the saddle D' are returned into contact with the lever A' by the spring G'.
- 50 The backing off saddle D' Fig. 5 and its base C' carry divisions which indicate the

stroke and which is made by the backing off saddle D' according to the position of the slide block F'. In order to account for the stroke of the saddle D', it is pushed from the 55 dead point position to the right in Fig. 5. The saddle is arranged to receive a double tool carrying rest or any other arrangement of rotatable saddle or reproducer.

What I claim is:—

1. In a lathe of the class described, a spindle, a main driving shaft, variable speed gears connecting said spindle and shaft; a lead screw, gears, including a differential, connecting the lead screw and said main 65 driving shaft; a cam shaft, gears including a differential connecting the cam shaft with the main driving shaft, a cam mounted for turning movement with and for longitudinal movement on the cam shaft; a base 70 mounted for longitudinal movement and having a nut arranged on the lead screw, a reproducing saddle on the base, and a lever and tappet to cause said saddle to be operated by the cam.
2. In a lathe of the class described, a spindle, a main driving shaft, variable speed gears connecting said spindle and shaft; a lead screw, gears, including a differential, connecting the lead screw and said shaft; 80 a cam shaft, gears including a differential connecting the cam shaft with the main driving shaft, a cam mounted for turning movement with and for longitudinal movement on the cam shaft; a base movable by 85 the lead screw, a lever articulated on the base, a reproducing saddle on the base, a support on the saddle, a guide block mounted on said support for sliding movement on the saddle, means to adjust the guide block 90 along the face of the lever to predetermine the stroke of the saddle, a tappet to cause the cam to operate the lever, and a spring acting on the saddle to impart return movement thereto.

In testimony whereof I have hereunto set my hand, in presence of two subscribing witnesses.

HONORÉ HAMPE.
